SEWING MACHINE CONTROL

Max Taigman, New York, N. Y.

Application April 4, 1936, Serial No. 72,719

13 Claims. (Cl. 192—02)

The invention relates to a control mechanism for a motor driven transmission of the type which are subjected to rapidly re-occurring intermissions in their operation and the invention specifically relates to an attachment to a sewing machine drive. The present disclosure constitutes a development and refinement of the inventions described in applicant's prior patents including 1,463,449, July 31, 1923 and 1,931,305.

10 October 17, 1933.

The primary object of the invention in this disclosure as was the primary object in the disclosure of similar construction in the above identified patents, is to combine a simplified compact, rugged construction for mounting an electric motor and associated sewing machine driving friction clutch in position relative to the control mechanism therefor, so that any of the standard makes of electric motors may be mounted in accurately located relation to the mechanism for controlling the clutch, for controlling the brake usual in such constructions and for controlling the current supply to the motor.

The disclosure in this application relates more particularly to refinements in details which additively contribute to the perfection of the disclosures in applicant's prior patents and to the commercially developed construction and details herein disclosed rather than to any radical departure from the disclosure in the above identified patents.

The present disclosure therefore features refinements in the organization of basically known parts; in making the parts as separately constructed units; in providing for accessibility to adjustable and replaceable parts and in economizing in the number and size of component parts and in the disposition of metal in the structural parts to provide for maximum strength and resistance to distortion while featuring lightness in weight of material.

Various other objects and advantages of the invention will be in part obvious from an inspection of the accompanying drawings and in part will be more fully set forth in the following particular description of one form of mechanism embodying the invention, and the invention also consists in certain new and novel features of construction and combination of parts hereinafter set forth and claimed.

In the accompanying drawings:

Fig. 1 is a view in front elevation of a preferred embodiment of the invention shown in its operative relation to an electric motor and associated friction clutch driven thereby and which

motor is hung from a sewing machine support and in which view the friction clutch is shown partly in vertical section and the control parts in its pulley-braking and clutch inoperative position;

Fig. 2 is a view showing the opposite side of the control device shown in Fig. 1 and with the electric motor, its clutch and the current controlling switch shown in ghost outline;

Fig. 3 is a plan view looking down upon the structure shown in Fig. 2;

Fig. 4 is a detailed view showing the connection between the main supporting frame and the switch box shown in Fig. 2 and with the parts slightly separated;

Fig. 5 is a detailed view showing a modified form of the connection between the casing and frame and taken on the plane indicated by the line 5—5 of Fig. 3;

Fig. 6 is a detailed perspective view showing the replaceable brake and outer end of the associated brake arm; and

Fig. 7 is a view corresponding to the mid-portion of Fig. 3 showing a modified form of vertically adjustable connections between the motor hanging bracket and the mechanism control unit particularly featured in this disclosure.

In the drawings and referring first to the showing in Fig. 1 there is disclosed a sewing machine table 10 on which is mounted a sewing machine 11 driven by belt which extends through the table 10 and is driven from pulley 13 in turn driven from electric motor. The motor and associated control unit hereinafter disclosed depends from bracket 15 secured to the underside of table 30 by bolts 16. The motor is provided with a driving shaft 17 which carries a side face type of friction clutch 18. This clutch includes a relatively fixed clutch element 19 provided with a long hub 20 which projects on the shaft 17 in opposite 40 direction from the clutch element 19 so as to provide a long bearing for element 19 on shaft 17 and in turn provide a long bearing for the hub 21 of the coacting clutch element 13, the periphery of which is grooved to form the pulley to receive the belt 12. A friction ring 22 is inserted in element 19 to provide a frictional drive between the elements 13 and 19 of the friction clutch when floating hub 21 of element 13 is moved to the right of the showing of Fig. 1 and 50 into its frictional clutching engagement to cause the motor to drive the sewing machine.

The bracket 15 is provided with a plurality of longitudinally extending motor mounting slots 23 so located as to accommodate different size 55

and makes of electric motors and arranged so that the base 24 of the motor may be adjustably mounted on the bracket and shifted in the direction of the length of the slots, that is in the direction of the axis of the motor shaft to locate the associated friction clutch horizontally relative to the control element of the unit hereinafter described. Bolts and nuts 25 are employed to secure the motor to the bracket in its horizontally adjusted position. The control unit or attachment designated 26 as a whole is designed to be mounted upon the bracket so as to permit vertical adjustment of the unit relative to the bracket and thus relative to the electric motor and its associated clutch carried by the bracket. For this purpose there is provided at the edge of the bracket beneath the sewing machine a wide upstanding channel member, which as shown at 27 in Fig. 3 extends parallel to the axis of the shaft, that is parallel to the length of the bracket, or which in the modified showing at 28 in Fig. 7 extends at right angles to the shaft, that is at right angles to the length of the bracket, but otherwise of identical construction so that the detail of the description on one will be sufficient for the other. In either case the channel member 27 or 28 is provided in its web 29 with a vertically extending slot 30 extending from the upper edge downwardly as shown in Fig. 2. The unit 26 includes a main supporting frame 31 in the form of a rugged cantilever arm terminating at its supported end in a wide rugged vertically extending bar 32 which fits within the channel member 27 or 28 and is of some material length so as to resist tendency of the unit to sag relative to its support in any direction. A bolt 33 extends through the slot 30 and is threaded into the bar so that when the bolt is tightened in place the bracket as a whole is rigidly secured to the bracket in such vertically adjusted position so as to bring the brake and clutch control elements hereinafter described into their proper operative position relative to the particular motor which happens to be mounted on the bracket. The supporting frame 31 projects horizontally from the bar, has its outer end slightly down-turned and terminates in a cylindrical and horizontally extending journaling boss 34. A short headed stub shaft 35 is mounted in the boss and is secured against end-wise movement by stop screw 36 threaded through the boss. The shaft is provided with a head 37 and fitted between this head and the adjacent end of the boss is a long hub 38 of a T-shaped bell crank lever 39 journalled for rocking movement on the shaft 35. The bell crank lever includes a long horizontally extending actuating arm 40 provided with apertures 41 and 42 in which may be selectively engaged a depending pull rod 43 leading to a foot pedal (not shown) and by means of which the device may be operated by the foot of the operator as is usual in such constructions. The bell crank lever also includes a depending clutch controlling arm 44 provided at its lower free end with an adjustable set screw 45 constituting an end thrust bearing element disposed in axial elongation of the shaft 35 and operatively disposed to engage the end wall 21' of the shiftable clutch element 21 to hold the same into its frictional clutching engagement with the friction band 22 on the element 19. The arm 44 is relatively short compared to the longer arm 40 so as to obtain a powerful leverage effect from the manually energized action in order to cause 75 a quick powerful interengaging of the friction

clutch faces. The bell crank lever also includes a relatively short upstanding arm 46 which carries a pivot pin 47 extending therethrough. A coiled retractor spring 48 has one end secured to the pin 47 between nuts 49 as shown in Fig. 3, the other end of which spring engages rugged post 49' formed integral with the supporting frame and projecting laterally therefrom at the curved portion where it merges into the bar 32 as particularly shown in Figs. 1 and 7. It is intended that spring 48 be a powerful spring capable of exerting a forceful braking action on the brake and insuring a quick return of the other elements of the control device and actuating pedal to their normal inoperative position. 15

Pivoted to pin 47 is a Z-shaped brake lever 50 having one end enlarged and overlapping the lever arm 40 as particularly shown in Fig. 3. A set screw 51 is threaded through the enlarged end and is disposed in bearing engagement with arm 40 so as to partake of its movement and at the same time to locate brake 52 at its opposite end in adjusted relation to the groove of the pulley at 13. The brake 52 is formed of any conventional braking material and in the illustrated case is formed of leather. This brake wears away rapidly and must be replaced from time to time. In order to facilitate the replacement without necessity of dismounting the control mechanism, the enlarged end of the brake 50 is provided with a wide head 53 as particularly shown in Fig. 6. This head is provided with a recess or opening 54 which extends in the plane of the pulley and thus in the plane of the brake. The brake is provided at its upper end 55 with a reduced rectangular upstanding portion 55 designed to fit in the recess 54 with a frictionally snug fit. In order to prevent transverse movement of the upper portion of the brake, the head 53 is provided on its under-side with a channel or groove 56 in which the upper unreduced end of the brake is contained.

The length of the set screw 51 is so proportioned that when it is desired to replace a worn brake with the fresh element, screw 51 is loosened to an extent to permit the brake to clear the pulley a distance sufficient to permit the mounting of the new brake in position into the under-side of the elevated head 53 without otherwise disarranging the pre-setting of the other parts. With the brake in position, the screw 51 is reset to give the desired pressure between brake pulley on the subsequent operation of the device. 45

It is, of course, understood that the parts are so proportioned that the brake 52 is located centrally above the pulley so that when lowered the curved under-side 57 of the brake will snugly engage the pulley perimeter and that the adjustable set screw 45 is in axial alignment with the clutch so as to direct pressure centrally thereon and along the direction of the axis of the motor shaft 35. Because of the necessity of bringing these parts into their proper position is the reason for the peculiar shape of the several associated parts. 60

The main supporting frame 31 provides a support for a switch box casing 58 hung therefrom and preferably detachably suspended therefrom. In so far as the parts within the casing are concerned, it may be assumed that they correspond to the showing in applicant's Patent 1,463,449, and that current is lead to the motor through a control switch, shown in dotted outline in Fig. 2, and which switch is in turn controlled by plunger 70 75

59 projecting upwardly from the casing. Also following structure similar to that disclosed in applicant's Patent 1,931,305, a switch control lever 60 is pivoted to a lug 61, in this case upstanding 5 from the rear side 62 in the casing and having the Z-shaped form shown in Fig. 3. One end of the lever 60 bears on plunger 59 and at the opposite end the lever is provided with a knife edge 62 which is disposed in the path of movement of 10 a laterally projecting leg 63 adjacent the free end of the manually actuating arm 40. The supporting frame is provided on one side thereof with a vertically extending, shallow slot 64 adjacent its outer end, and located in this slot is an up- 15 standing post 65 formed integral with the rear side 62 of the casing 58. This slot 64 and post 65 are provided as shown in Fig. 4 with registering bolt holes 66 through which may be inserted a standard type of nut bolt fastenings, or as suggested in the modified form shown in Fig. 5, a threaded stud 67 may be formed integral with the supporting frame and extend therefrom centrally of the slot 64. The bolt holes 66 of the post is inserted over the stud 67 and nut 68 used to 20 snugly secure the parts in position. It will be understood from this construction that the wide post in its engagement with the similarly wide slot provides a rugged suspension means for the casing and which tend to defeat tendency of the 25 casing to swing. The post 65 is provided integrally therewith with a hook 69 for securing in place an electric lead shown in dotted lines in Fig. 3 and extending from the switch casing to the electric motor.

30 In operation and assuming that the bracket 15 is properly located relative to the sewing machine 11, the electric motor 14 is at first temporarily located in position on the bracket with its friction clutch carrying end disposed opposite arm 44 and with the brake 52 located above the associated pulley. Then by a refined adjustment of 35 the motor 14 in the slots 23 and at the same time by means of the vertical adjustment of the unit as a whole in the slot 30, the several parts are 40 accurately located relative to the other and when so located, no further adjustment is required.

To operate the device, the operator presses conventionally on the foot pedal which lowers the rod 43, shifts the arm 44 to the right of the showing in Fig. 1 to cause the clutch to become active and thus cause the motor 14 to drive the sewing machine through the belt 12. Simultaneous with this action, the brake 52 is elevated out of its clutching position with the pulley, tension is 45 stored in the spring 28 and plunger 59 is lowered to close the circuit to the electric motor. Releasing foot pressure on the pedal will permit spring 43 in its collapsing movement to release the friction clutch which automatically brakes the driving connection between the motor and sewing machine, releases the electric switch and acts to force the brake into its normal pulley braking position shown in Fig. 1 to suddenly stop the operation of the sewing machine as is well known in this art.

50 I claim:

1. In a device of the class described the combination of a hanging bracket, an electric motor adjustably secured to the bracket to hang therefrom and provided with a horizontally extending 55 motor shaft, two elements of a friction clutch supported from the motor shaft, one secured directly to the shaft to turn therewith and provided with two hubs extending axially from opposite ends thereof, the other clutch element 60 slidably mounted on one of the hubs and having

its periphery grooved to form a driving pulley, a control mechanism comprising a single unit adjustably supported from the end of the bracket adjacent the friction clutch and including a unit supporting frame having a broad bearing bar having a vertically adjustable engagement with the bracket, a manually actuated bell crank lever supported by the frame and having its axis fixed relative thereto, said bell crank lever having one arm disposed for engaging the pulley forming element of the friction clutch to move the same into clutching engagement with its companion, a brake lever pivoted to the bell crank lever and including a brake engaging in the groove of the pulley to brake the same and adjustable means between the bell crank lever and the brake lever to adjust the brake relative to the pulley, and means for controlling the operation of the electric motor including a switch box demountably secured to the unit supporting frame, a horizontally disposed switch controlling lever pivoted to the box, extending beside and substantially parallel to one arm of the bell crank lever and having one end disposed in the path of movement of the manually actuated lever to be actuated thereby.

2. In a device of the class described, an electric motor for driving a sewing machine and a mounting therefor including a friction clutch drive carried by the motor, fixed relative to its axis of rotation and acting between the motor and sewing machine, said mounting comprising a bracket provided with a plurality of slots for locating the motor in a horizontally adjusted position when hung from the bracket, said bracket including an upstanding wide channel member projecting from one edge thereof, a control unit including a supporting frame including a wide bar fitted in the channel and secured flatwise therein in vertically adjustable position, thereby to locate the parts of the unit relative to the adjustably located motor, said wide channel and wide bar interengaging to defeat all relative movement except vertically, in the direction of the channel, said unit including a manually actuated control lever pivoted to the supporting frame, a brake, an actuating lever for controlling the friction clutch and a circuit control lever for controlling the motor, the brake, clutch and motor control levers being interconnected and actuated by the manually actuated control lever.

3. In a device of the class described, the combination of a bracket for supporting an electric motor provided with a clutch mounted on the motor shaft and including a clutch pulley, said motor and bracket being cooperating, means for securing the motor in position adjustable in the direction of the axis of its shaft, a control unit supported from the bracket in fixed relation relative to adjustments horizontally, said unit constituting a horizontal extension from the bracket, and said bracket and unit provided at their interengaging ends with cooperating means including vertically extending wide spreading interengaging surfaces for securing the unit to the bracket in vertically adjustable and otherwise fixed relation and a manually actuated control lever fixedly pivoted to the unit and having a depending clutch actuating arm fixed for movement in the plane containing the axis of the motor shaft and having a brake actuated by the control lever and engaging the upper side of the pulley to brake the same.

4. In a device of the class described, the combination of a hanging bracket for supporting an

electric motor provided with a clutch mounted on the motor shaft, said motor and bracket having cooperating means for securing the motor in position adjustable solely in the direction of the axis of its shaft and fixed in every other direction, a control unit including a main frame constituting a cantilever structure supported from the bracket in fixed relation relative to adjustments horizontally and contained for the most part above the base of the motor, said bracket and frame 31 provided with cooperating means for securing the unit to the bracket in vertically adjustable relation and a manually actuated control lever fixedly pivoted to the frame at its free end and having a clutch actuating arm extending both above and below the motor base and fixed for movement in the plane containing the axis of the motor shaft.

5. In a device for controlling a friction clutch, the combination of a bell crank lever fulcrumed to rock about a fixed axis and comprising three arms in the same vertical plane, one arm being relatively long and forming a manually actuated power arm, another relatively shorter arm provided with an adjustable end thrust element for actuating the friction clutch, to move the same into its clutching position, a brake lever fulcrumed to the third and shortest arm, said brake lever forming in effect a fourth arm to the bell crank lever, and provided at one end with a brake for engaging one of the clutch elements to brake the same and the opposite end of the brake lever provided with a set screw for engaging the actuating lever and thus regulating the operative position of the brake relative to its associated clutch element and a long powerful coiled retractor spring having one end engaging said shortest arm extending substantially at right angles to the length of said shortest arm and tending to rotate the bell crank lever in a direction to cause the end thrust element to move away from the clutch and to cause the brake to move into its braking engagement and a pivot pin for journaling the brake lever to said short arm and to which one end of the spring is secured.

6. In a device for controlling a friction clutch, the combination of a bell crank lever fulcrumed to rock about a fixed axis and comprising three arms all contained in the same vertical plane, one arm being relatively long and forming a horizontally extending manually actuated power arm, another relatively shorter arm depending from the power arm and provided with an adjustable end thrust element for actuating the friction clutch, to move the same into its clutching position, a brake lever fulcrumed to the third and shortest arm, said brake lever forming in effect a fourth arm to the bell crank lever and contained substantially in said plane, and provided at one end with a brake for engaging one of the clutch elements to brake the same and the opposite end of the brake lever overlapping the power arm and provided with a set screw for engaging the actuating lever and thus regulating the operative position of the brake relative to its associated clutch element.

7. In a device of the class described, the combination of a bracket, an electric motor hung from the bracket, a friction clutch having one element secured to the motor shaft and its companion slidably mounted on the first named element and including a pulley, means for adjusting the motor on the bracket horizontally and in the direction of the axis of its motor shaft, an

attachment carried by the bracket, vertically extending means between the bracket and the attachment for adjusting the attachment vertically relative to the pulley forming element of the clutch, said attachment including a plurality of levers interconnected to operate in unison, one constituting a lever for controlling an electric switch in turn controlling the motor, a lever for engaging the pulley to actuate the clutch and a lever provided with a brake for engaging the pulley to stop its rotation when the clutch is disengaged and means for adjusting the brake lever to cause it to fit the pulley when motor and associated friction clutch element have to be adjusted relative to pulley lever. 15

8. In a device of the class described, the combination of a motor supporting bracket, an attachment adjustably supported directly from the bracket and including a supporting frame, a manually actuated lever journalled on the supporting frame, said post and frame coacting to prevent swinging movement of the casing and provided with a ledge projecting laterally from one side thereof, a switch casing provided with a post detachably secured to the supporting frame, a switch controlling lever journalled on the casing and having one end positioned in the path of movement of the ledge to be actuated by the manually actuated lever and otherwise disconnected therefrom. 20

9. An attachment for controlling the driving connection between an electric motor and a pulley for driving a sewing machine, said attachment including a supporting frame provided with means for mounting it in adjustable relation to the motor, said frame provided on one side thereof with a channel shaped slot and provided with an integral stud projecting into the slot, a switch containing casing provided with a broad, flat post fitted in the channel of the slot 25 and provided with an aperture in which the stud is fitted and said post provided just beneath the frame with an integral hook about which may be trained an electric cable leading to the casing. 30

10. In a device of the class described, the combination with an electric motor for driving a friction clutch and in which said clutch includes a pulley, of a control mechanism for braking the pulley elements of the clutch when the clutch is in its inoperative, non-driving condition, said mechanism including a supporting frame, means for mounting the frame in adjustable relation to the motor and to the clutch, a manually actuated bell crank lever pivoted to the frame and including a depending arm for controlling the clutch 35 and a recess extending through the arm at the recess, a brake lever pivoted to the bell crank lever and movable therewith, said brake lever provided with an arm overlapping the pulley, said arm provided with an elongated slot extending 40 parallel to the plane of the pulley and a recess extending through the arm at the slot, a brake having its upper end demountably fitted in both the slot and recess, frictionally engaging the brake lever and having its underside curved to 45 the curvature of the pulley groove and acting to brake the pulley simultaneously with the releasing of the clutch. 50

11. In a device of the class described, the combination of a bracket, a horizontally extending 55 supporting frame including a wide bar having a vertically adjustable connection with the bracket, said frame provided adjacent the bar with a spring holding finger and provided at the other end with a stub shaft bearing and also provided 60

- on one side thereof with a flat vertically extending slot, a casing including a flat bar demountably fitted in said vertical slot, a stub shaft mounted in said bearing, a bell crank lever journaled on said shaft, one arm of the lever adapted to be manually actuated, another arm extending substantially at right angles thereto and provided at its free end with an adjustable screw constituting a clutch actuating end thrust bearing member, a pivot pin on the side of the lever fulcrum opposite said last named line, a brake lever provided with a brake journaled on said pivot pin and horizontally extending coiled spring having one end secured to said finger and the other end secured to the pivot pin and tending to swing the bell crank lever and the brake lever in the direction to apply the brake and release the associated clutch.
12. In a device of the class described, the combination of a clutch, one element of which is a pulley, an actuating lever having a fixed fulcrum and having at one end an adjustable thrust bearing for engaging the clutch to move the same into clutching position, a brake lever fulcrumed to the actuating lever and provided at one end with a recess extending therethrough, and a channel extending across the recess on the side thereof facing the pulley, a brake for engaging the pulley to intercept rotation thereof, said brake having an end replaceably inserted in the recess and having a shoulder portion adjacent the end and
- fitted in said channel and adjustable means between the other end of the brake lever and the actuating lever for adjusting the brake relative to the pulley, said adjustable means being of sufficient length to permit the brake carrying end of the brake lever to be moved temporarily away from the pulley a distance sufficient to permit the end of the brake to clear both the recess and channel and to permit the insertion of a new brake in the brake lever without necessity of demounting the same from the actuating lever.
13. In a device of the class described, the combination of a supporting frame provided at one end with means for mounting it in place, said frame having its opposite end enlarged and provided on one side of the enlarged end with a vertically extending slot, a switch box casing including a plunger protruding through the top of the casing, a lug projecting from the top of the casing, a switch control lever fulcrumed to the lug and having one end overlapping and bearing on top of the plunger to control the same and having its opposite end projecting beyond the outlines of the casing, a post projecting above the casing and demountably fitted in the slot, means for securing the post to the frame, and an actuating lever pivoted to the frame and adapted to engage the projecting end of the switch lever to actuate the same.

MAX TAIGMAN. 30
